12 Claims. (Cl. 1-2)

1

This invention relates to manually operated wire stitching machines.

In the present specification and in the appended claims, the words "manually operated," or equivalent expressions, are to be taken as covering operation by hand or by foot.

An object of the present invention is to provide a manually operated wire stitching machine of generally improved construction, whereby the disadvantages of the known arrangements are avoided or minimised.

The invention consists broadly of a manually operated wire stitching machine, comprising cam means having cam surfaces for actuating a staple preparing mechanism adapted to feed wire and cut the same to produce a staple blank, said cam means also having cam surfaces for actuating a forming and driving mechanism adapted to form a prepared blank into a staple and to drive the latter into the work, and further comprising a lever, arranged to be rocked by foot or by hand, such rocking motion of said lever being imparted to said cam means to produce corresponding angular oscillation thereof, a single complete oscillation of said cam means causing simultaneous actuation of both said blank preparing mechanism and said forming and driving mechanism, whereby a staple is formed and driven into the work whilst a further blank is prepared for forming and driving during the next succeeding complete oscillation of the cam means.

For a better understanding of the invention and to show how it may be carried into effect, the same will now be described, by way of example, with reference to the accompanying drawings, in which:

Figure 1 is a partial front elevation of a foot operated wire stitching machine according to the invention.

Figure 2 is a side elevation according to Figure 1.

Figure 3 is a detail view (drawn to a larger scale than Figures 1 and 2) showing a front elevation of the stitching head.

Figure 4 is a side elevation, partly in section along the line IV-IV of Figure 3,

2

Figure 5 is a view similar to that shown in Figure 3, but with the various parts shown in their position at a different stage in the stitching cycle.

5 Figure 6 is a side elevation, partly in section along the line VI-VI of Figure 5.

Figure 7 is a plan view of the stitching head.

Figure 8 is a partial horizontal sectional view taken along the line VIII-VIII of Figure 3.

10 Figure 9 is a partial front elevational view of the stitching head with the front covers and certain of the stitching head mechanism removed.

Figure 10 is a sectional view taken along the line X-X of Figure 9 but with the front covers in place, and

15 Figure 11 is a partial horizontal sectional view taken along the line XI-XI of Figure 9 with the front covers in place.

Referring to Figures 1 and 2, the machine comprises a frame 1 having at its upper end an arm 2 provided with housings 3 and 4 for the front and rear bearings of a drive-shaft 5. The housing 3 carries a back-plate 6 of the stitching head to which is secured a covering plate 6a, in which 20 a staple forming element 7 and a staple driving element 8 reciprocate along a common vertical axis A-A (Figure 1). In the example given, the drive shaft 5 extends from the stitching head to the rear of the machine and the axis of the shaft is substantially normal to the plate in which wire staples are formed and driven into the work. As shown in Figure 1, the axis of the drive-shaft 5 is also located above, and laterally off-set with respect to, the path of motion of the staple forming and driving elements.

30 At the lower end of the frame 1, there is pivotally mounted the actuating means which, in the present embodiment, comprises a lever in the form of a pedal 9, which rocks about a shaft 10 extending transversely of the machine frame. At 35 the rear of the machine, there is provided a substantially upright connecting rod 11, the lower end of which is connected by a pivot pin 12 to the pedal 9. The upper end of the connecting rod 11 is formed with a lug 13 which is rotatably mounted upon a pin 14 carried by a crank 15 se-

cured to the rear end of the drive-shaft 5. An adjustable abutment, consisting of a collar 16 having a fixing screw 17, is mounted on the connecting rod 11 to provide an operative connection between the rod and the anvil clinching mechanism of the machine, indicated generally at 18. Both the clinching mechanism 18, and the adjustable table 19 upon which the work can be supported, are, in themselves, well known in wire stitching machines, and further description thereof is unnecessary.

As shown more particularly in Figures 9 and 10, a cam plate 20 is eccentrically mounted upon the forward end of the drive-shaft 5 located within the stitching head. Two cam grooves 21 and 22 are formed in one face of the cam plate 20 and, as shown in Figure 9, the grooves are disposed on that side of the centre of motion of the cam plate, which is of greatest radius. The cam grooves are each of irregular arc-shape formation and the groove 21 is engaged by a follower 23 rotatably mounted upon a pin 24, secured to the staple former 7, while the groove 22 is engaged by a follower 25 rotatably mounted upon a pin 26 secured to the staple driver 8. The cam plate 20 is also formed, on the same side of the centre of motion as the arc-shaped cam grooves, with a lower cam periphery 27 arranged to engage a follower 28 (see Figure 8) rotatably mounted in a block 29 which carries wire cut off mechanism as hereinafter described.

The cam plate 20 is furthermore provided with an upper cam periphery 30, oppositely disposed with respect to the lower periphery 27. The upper cam periphery is adapted to engage a cam follower 31 rotatably mounted upon a pin 32 carried at the extremity of one arm 33 of a wire feed lever 34 pivotally mounted at 35 in the back-plate 6 of the stitching head. A spring 36, arranged between an upward extension 31 of the lever 34 and a fixing screw 38 mounted in the plate 6, is adapted to urge the lever 34 in a clockwise direction so as to maintain the follower 31 in engagement with the associated cam periphery 30.

The staple forming and driving elements 7 and 8, mounted in the stitching head 6a, are enclosed by a cover plate 39, hingedly mounted at 39a upon the front of the stitching head 6a. In the lower part of the cover plate there is slidably mounted a forming anvil 40 which is urged by a leaf spring 41 from the plane Y-Y (see Figure 4), in which wire is fed to the forming anvil and cut-off to form a staple blank w, to the plane Z-Z (see Figure 6) in which the staple is formed and driven into the work.

In power driven machines having rotary driving cams, the inward movement of the forming anvil is determined by the return motions of the staple forming and driving elements, these motions being such that the former is retracted in advance of the driver, so that the forming anvil is free to move inwards as soon as the driver withdraws from engagement with the inner end of the forming anvil.

In the present arrangement, since a reciprocating or rocking motion is imparted to the cam plate 20, the return motions of the staple forming and driving elements, and also of the wire feed and cut-off levers, are identical but the reverse of the respective forward motions.

Latch mechanism is therefore provided to ensure that the forming anvil 40 and the wire blank w do not move forwardly towards the staple forming position Z-Z until both the staple

driver and former have almost reached their upper dead centres.

As shown in Figures 3 to 6, and Figure 10, the latch mechanism comprises a vertical latch-bar 42 slidably mounted in a vertical guideway formed in the cover-plate 39 and maintained in position by a plate 43 screwed to the cover-plate. The latch-bar is formed at its lower end with an extension 44 which, when the bar is in its lowermost position, is adapted to engage behind shoulder 45 on the forming anvil 40 (Figure 8), to hold the latter in an outer, or wire feeding, position. The upper end of the latch-bar is bent over to form a flange 46 which extends through a slot 47 in the cover-plate, into the stitching head, the flange 46 being engageable by the upper end of the staple driver 8, as the latter approaches its top-dead-centre. The latch-bar is urged downwardly by a compression spring 48 arranged between the flange 46 and a fixed pin 49 in the cover-plate.

Wire stock is fed to the forming anvil from a spool 50 rotatably mounted upon a support 51 extending upwardly from the stitching head. The wire passes around a lateral guide 52, secured to the lower end of the wire feed lever 34, and then through a slot 53 formed in the lever 34. During the feeding motion of the lever 34, the wire is gripped, in known manner, by a spring loaded gripper 54 pivotally mounted on the lever 34.

The wire stock then passes through a slot 55 formed in the lower end of a support-plate 56 mounted on the stitching head. The support-plate 56 carries a spring loaded non-return gripper 57 which is adapted to control the wire which has been fed through a cutting tube 58 secured to the lower part of the support-plate. The support-plate has an arm 59 engageable by a projection 60 on the wire feed lever 34, and the said support-plate is adjustably secured to the stitching head by means of a thumb-screw 61 so as to provide for adjustment in the length of wire fed to the forming anvil. A datum-mark 62 on the support-plate 56, which mark reads against a scale 63 on the front of the stitching head, facilitates the positioning of the plate 56 according to the required length of wire feed.

The cut-off mechanism comprises a knife 64 secured to a forwardly projecting part 65 (see Figure 8) of the block 29, which latter is pivotally connected to the support-plate 56 and is loaded by a spring 66, so that the cam follower 28 on the block 29 is urged upwardly to engage the lower cam periphery 27 of the cam-plate 20. The knife 64 is arranged to cut off a length of wire fed to the forming anvil, when the follower 28 is depressed by a cam projection 27a on the lower cam periphery 27.

The latch mechanism is operatively connected to the cut-off mechanism by means of a trip device comprising a trip-lever 67, mounted upon a pivot pin 68 secured to the support-plate 56. The lever 67 carries at its free end a slider 69 adapted to slide along a transverse guide-way 70 formed in the latch-bar 42. The lever 67 also has a nose 71 adapted to engage an abutment 72 on the forward part 65 of the block 29, so as to hold the latch-bar in its elevated position. The part 65 is also provided with a pin 73 engageable with the non-return gripper 57, to hold the latter out of engagement with the wire during the wire feed motion.

In order to indicate the functional relationship between the described elements of the stitching

mechanism, the cycle of operations will now be described from the moment when the parts of the stitching head mechanism are approximately in the position indicated in Figures 3 and 4, and the staple former and driver are about to descend, to form and drive a staple into the work (indicated diagrammatically at W in Figure 6). The wire feed lever 34 is at, or near, its fully retracted position, and the lower cam periphery 27 of the cam-plate 20 has moved from engagement with the follower 28 so that the block 29 which carries the cut-off knife 64 is elevated and the pin 73, carried by the block 29, is in engagement with the non-return gripper 57, so as to hold the gripper 57 in an inoperative position. The forming anvil 40, carrying a cut-off blank *w*, is held in the innermost position by the the spring 41, so that the blank *w* is located in the staple forming and driving plane. The latch-bar 42 is held in its uppermost position by means of the trip lever 67, rotation of the latter being prevented by engagement of the nose 71 of the trip lever, with the abutment 72 on the block 29.

Following the sequence of events up to this point, the foot pedal 9 is depressed, so that the upright connecting rod 11 is displaced upwardly causing the crank 15 and the drive-shaft 5 to rock the cam-plate 20 in a clockwise direction. The staple former 7, followed by the driver 8, moves downwards to engage the free ends of the wire blank *w* and to form the legs of the staple over the forming anvil 40. During this part of the cycle, the latch-bar 42 continues to be held in its elevated position by the trip lever 67. As the driver moves down, it engages the inner end of the forming anvil and forces the latter outwardly, into the wire feed position. The cam periphery 30 engages the follower 34 causing the wire feed lever 34 to rock in an anti-clockwise direction so that wire stock is fed through the cutting tube 58 to the forming anvil. As the staple former 7 reaches its lower dead centre, the follower 28 of the cut-off mechanism is engaged by the lower cam projection 27a causing the cut-off knife 64 to move across the end of the tube 58, thereby to cut off the length of wire fed to the forming anvil. As the cut-off knife is displaced, the pin 13 disengages from the non-return gripper 57, permitting the latter to engage and hold the wire stock. The trip lever 67 is simultaneously also released from engagement with the abutment 72, whereupon the latch-bar 42 moves downwardly, under the action of the spring 48, so that the extension 44 of the latch-bar engages behind the shoulder 45 of the forming anvil, whereby the forming anvil is held in the retracted, or wire feed, position. The elements are now in the relative positions indicated in Figures 5 and 6. Continued clockwise rotation of the cam-plate 20, causes the staple former and driver to move downwards to complete the driving operation and the final clinching of the staple to the work.

Upon release of the actuating pedal, the weight of the connecting bar 11 and the associated linkage, causes the drive-shaft 5 and the cam-plate 20 to rock in an anti-clockwise direction. Thereupon the staple driver and former move upwardly on their return motion, and the wire feed lever 34 also commences its return motion in a clockwise direction. The return motions of these elements are similar to, but the reverse of, the respective forward motions; thus the staple driver moves upwardly in advance of the staple former. However, the forming anvil is unable to move inwardly with the cut-off blank, for the reason that

the forming anvil is now held in the wire feeding position by the extension 44 of the latch-bar. As the driver 8 approaches its upper top-dead-centre it engages the flange 46 of the latch-bar and lifts the latch-bar, thereby freeing the forming anvil 40 and permitting the latter, together with the cut-off blank, to move inwards for the next staple forming and driving cycle. Meanwhile, the wire feed lever 34 has reached its fully retracted position in which the projection 69 engages the arm 59 of the support-plate 55, and the lower cam periphery 27 of the cam-plate has moved from engagement with the follower 28 of the cut-off mechanism. As a result, the block 29 of the cut-off mechanism has sprung upwardly under the action of the spring 66, so that the pin 13 re-engages and holds the non-return gripper 57 in its released position ready for the feeding of a fresh length of wire during the next succeeding cycle of operations.

It is to be noted that the crank 15, the connecting rod 11, and their associated parts, are preferably so constructed and arranged as substantially to balance, on the one hand, the cam-plate and, on the other hand, the operating pedal 9. In this manner, the minimum of effort is required to depress the pedal in order to effect a staple forming and driving stroke, while as soon as pressure is released from the pedal, the parts will automatically return to their normal positions.

It will be appreciated that the pedal arrangement for operation of the machine by foot, may be replaced by an operating lever arranged for manual operation of the machine.

The stitching head, as hereinbefore described, permits a relatively small cam-plate to be employed and this cam-plate may be secured to the drive-shaft and completely enclosed within the stitching head, in the manner of a power driven machine. The cam tracks and peripheries for the followers of the various elements are so disposed about the centre of motion of the cam plate as to facilitate the balancing of the cam, while the cam paths are shorter, and a more favorable leverage is obtained than that afforded by the drive means hitherto employed on manually or foot operated stitching machines. In common with power driven machines, the operative connections between the staple former and driver, the wire feed mechanism and the cut-off mechanism, are such as to allow the maximum period for the feeding of fresh lengths of wire to the forming anvil, ready for the following stitching cycle. This is of particular importance in connection with operator driven machines so as to ensure that a constant length of wire is fed to the forming anvil during each cycle. Furthermore, the arrangement reduces the possibility of wire buckle occurring should any incomplete stroke inadvertently be made.

The construction enables an operator drive machine to have a similar form and cycle to, and to retain practically all the advantages of, a power drive wire stitching machine.

It is also common practice to form and drive the stitches in a direction at right-angles to that shown in the example given. In this case the housing 6 and all mechanism attached thereto is disposed parallel to the actuating shaft 5 shown in Figure 2, and a right-angle drive such as a pair of mitre bevel wheels is introduced between the shaft 5 as shown in Figure 2 and a shaft 5 shown in Figure 9, the latter becoming a separate short stub shaft housed in the framing and

carrying cam 20 at the operative end, no part of the invention being thereby affected.

I claim:

1. A manually operated wire stitching machine, comprising a frame, a shaft mounted for rocking motion in said frame, cam means mounted on said shaft, manually operated lever means for rocking said shaft and producing a corresponding angular oscillation of said cam means, staple preparing mechanism for feeding wire stock and for cutting the fed wire to produce a staple blank, staple forming and driving mechanism for forming a prepared blank into a staple and driving the staple into the work, means for delivering a prepared blank to said driving and forming mechanism, cam surfaces on said cam means for causing simultaneous actuation of both said blank preparing mechanism and said forming and driving mechanism during each complete angular oscillation of said cam means, and means for controlling the operation of said delivery means, said controlling means being actuated in timed relationship with said forming and driving mechanism, so that while a staple is formed and driven into the work a further blank is prepared and delivered into position for forming and driving during the next succeeding complete angular oscillation of said cam means.

2. A manually operated wire stitching machine, comprising a frame, a shaft mounted for rocking motion in said frame, cam means mounted on said shaft, manually operated lever means for rocking said shaft and producing a corresponding angular oscillation of said cam means, staple preparing mechanism for feeding wire stock and for cutting the fed wire to produce a staple blank, a member for receiving and holding the fed wire during the cutting of the staple blank, staple forming and driving mechanism for forming a prepared blank into a staple and driving the staple into the work, latch means actuated in timed relationship with said forming and driving mechanism for causing said member to deliver a prepared blank into the forming and driving position, and cam surfaces on said cam means for causing, during each complete angular oscillation of said cam means, simultaneous actuation of both said blank preparing mechanism and said forming and driving mechanism, so that a staple is formed and driven into the work during each complete angular oscillation of the cam means and a further blank is prepared while delivered into position ready for forming and driving during the next succeeding complete angular oscillation of said cam means.

3. A manually operated wire stitching machine, comprising a frame, a shaft mounted for rocking motion in said frame, said shaft extending in a direction substantially normal to the plane in which staples are formed and driven into the work, cam means mounted on said shaft for angular oscillating motion in a plane substantially parallel to the plane in which staples are formed and driven, manually operated lever means for rocking said shaft and producing a corresponding angular oscillation of said cam means, staple forming and driving elements mounted for reciprocation along a common axis for forming and driving staples into the work, means for feeding wire along a line removed from and parallel to the plane in which staples are formed and driven, a member for supporting the fed wire in the feeding position, means for cutting off the fed wire to produce a staple blank, cam surfaces on said cam means for simultaneously actuating said forming

and driving elements, and said wire feeding means and said cut off means, during each complete oscillation of said cam means, and means actuated in timed relationship with said forming and driving elements for permitting the wire supporting member to deliver a staple blank into the forming and driving position, so that during each complete oscillation of the cam means a staple is formed and driven into the work and a further blank is prepared and delivered into position ready for forming and driving during the next succeeding complete oscillation of the cam means.

4. A manually operated wire stitching machine, comprising a frame, a shaft mounted for rocking motion in said frame, cam plate eccentrically mounted on said shaft, manually operated lever means for rocking said shaft and producing a corresponding angular oscillation of said cam plate, staple forming and driving elements mounted for reciprocation along a common axis for forming and driving staples into the work, cam grooves in said cam plate for reciprocating said elements to form and drive a staple into the work during each complete angular oscillation of said cam plate, means for feeding wire along a line removed from and parallel to the plane in which staples are formed and driven, a member displaceable transversely with respect to the forming and driving elements and urged during the forward motion of the driving element into the wire feed position to receive the fed wire, means for cutting off the fed wire to produce a staple blank, cam peripheries on said cam plate for actuating said wire feeding means and said cut-off means during the actuation of said forming and driving elements, latch mechanism for holding the blank supporting member in the wire feed position during the greater part of the return motion of the driving element, and means for releasing said latch mechanism at the completion of the return stroke of the driving element to permit said member to deliver a fresh blank into position ready for forming and driving during the next succeeding complete oscillation of said cam plate.

5. A manually operated wire stitching machine, comprising a frame, a shaft mounted for rocking motion in said frame, a cam plate eccentrically mounted on said shaft, manually operated lever means for rocking said shaft and producing a corresponding angular oscillation of said cam plate, a forming element and a driving element mounted for reciprocation along a common axis, cam surfaces on said cam plate for actuating said forming and driving elements to form and drive a staple into the work during each complete angular oscillation of said cam plate, means for feeding wire stock along a line removed from and parallel to the plane in which staples are formed and driven, a spring urged forming anvil movable transversely with respect to the forming and driving elements, means for holding said anvil in the wire feed position to receive the fed wire during the forward motion of said forming and driving elements, means for cutting a staple blank from the fed wire, cam surfaces on said cam plate for actuating said wire feed means and said cut-off means to produce a staple blank during the actuation of said forming and driving elements, latch means movable into and out of engagement with said forming anvil, trip means for holding said latch means in inoperative position during the downward motion of said forming element, means operated in timed relationship with said cut-off means for releasing said trip means and permit-

ting said latch means to engage and hold the forming anvil in the wire feed position during the greater part of the return motion of said driving element, and means for returning said latch means to inoperative position when said driving element reaches the limit of its return motion to cause said forming anvil to bring the prepared staple blank into position ready for forming and driving during the next succeeding complete oscillation of said cam plate.

6. A manually operated wire stitching machine as claimed in claim 5, wherein the latch means comprises a latch-bar slidable vertically in the frame constituting the stitching head, spring means acting on the upper end of the latch-bar and urging said latch-bar downwardly, an extension at the lower end of said latch-bar engageable with a shoulder on said forming anvil to hold the latter in the wire feed position during the greater part of the return motion of the driving element, and a flanged-part at the upper end of said latch-bar, said flanged part extending into the stitching head and being engageable by the staple driving element at the termination of the return motion of said latter element to lift the latch bar and permit the forming anvil to present a prepared blank into the forming and driving position.

7. A manually operated wire stitching machine comprising a casing constituting a stitching head, a drive shaft mounted for rocking motion in said casing and disposed substantially normal to the plane in which staples are formed and driven, a cam plate eccentrically mounted on said shaft, manually operated lever means for rocking said shaft and producing a corresponding angular oscillation of said cam plate, a forming element and a driving element mounted for reciprocation along a common axis, cam grooves in said cam plate for actuating said forming and driving elements to form and drive a staple into the work during each complete oscillation of said cam plate, said cam grooves being disposed on that side of the centre of motion of the cam plate which is of greatest radius, means for feeding wire stock along a line removed from and parallel to the plane in which staples are formed and driven, a spring urged forming anvil slidably mounted in the stitching head and displaceable transversely with respect to the forming and driving elements, means for holding said forming anvil in the wire feed position to receive the fed wire, means for cutting the fed wire to produce a staple blank, an upper cam periphery on said cam plate for actuating said wire feed means during the downward motion of the forming and driving elements, a lower cam periphery on said cam plate for actuating said cut-off means during the downward motion of said forming and driving elements, and means for releasing said forming anvil as the driving element reaches the end of its return motion, and causing said anvil to deliver a prepared blank into position for forming and driving during the next succeeding complete oscillation of said cam plate.

8. A manually operated wire stitching machine as claimed in claim 7, wherein the drive shaft is mounted in said casing for angular oscillating motion about an axis extending from the stitching head to the rear of the machine, and wherein there is provided at the rear of the machine a vertically displaceable connecting rod, crank means between the upper end of said connecting rod and said drive shaft for imparting angular oscillating motion to said drive shaft by vertical

reciprocation of said connecting rod, an operative connection between the lower end of said connecting rod and the manually operable lever means, said latter means comprising a treadle pivotally mounted at the lower end of the frame, and adjustable abutment means intermediate the ends of said connecting rod for actuating anvil clinching mechanism of the machine.

9. A manually operated wire stitching machine as claimed in claim 7, wherein the said cut-off means comprises a block pivotally mounted in the stitching head, a cut-off knife mounted on said block, a cam follower on said block, spring means for urging said follower into engagement with the lower cam periphery on said cam plate, said lower cam periphery producing displacement of said block and knife to cut off a staple blank during the downward motion of said forming and driving elements.

10. A manually operated wire stitching machine as claimed in claim 7, wherein the means for cutting-off the fed wire comprises a block pivotally connected to a support plate, adjustably mounted in the stitching head, a cut-off knife secured to said block, a cam follower on said block engageable with the associated cam periphery on said cam plate, spring means for urging said cam follower into engagement with said cam periphery, said cam periphery depressing said block and said knife to cut-off a staple blank during the downward motion of the staple forming and driving elements.

11. A manually operated wire stitching machine as claimed in claim 10, wherein the support plate carries means for gripping the wire stock during the return motion of said wire feed means, and wherein there is provided on said pivoted block, a pin engageable with said wire gripping means to hold the latter out of engagement with the wire stock during the feed motion of the wire feed means.

12. A manually operated wire stitching machine comprising a frame, a stitching head on said frame, a drive shaft extending from the stitching head to the rear of said frame, a cam plate fixedly mounted on the forward end of said drive shaft and disposed within the stitching head, manually operated lever means for rocking said shaft and producing a corresponding angular oscillation of said cam plate, staple forming and driving elements mounted in said stitching head for reciprocation along a common axis for forming and driving staples into the work, cam grooves in said cam plate for actuating said forming and driving elements during each complete oscillation of said cam plate, means for feeding wire along a line removed from and parallel to the plane in which staples are formed and driven, an upper cam periphery on said cam plate for operating said wire feed means during the downward motion of said forming and driving elements, a spring urged forming anvil slidably in said stitching head transversely with respect to the forming and driving plane, means for displacing said anvil into the wire feed position

65 to receive the fed wire during the downward motion of said forming and driving elements, a support plate adjustably secured to the stitching head, a block pivotally mounted on said support plate, a cut-off knife carried by said block, a lower cam periphery on said cam plate for tilting said block and said knife to cut-off a staple blank during the downward motion of the staple forming and driving elements, a vertical latch-bar 70 slidably mounted in the stitching head, a trip

device engageable with said block for holding said latch-bar in an upper position during the downward motion of the forming and driving elements, means operative upon actuation of said knife to release said trip device and allow said latch-bar to engage and hold said forming anvil and the cut-off blank in the wire feed position, during the greater part of the return motions of the staple forming and driving elements, and means for returning said latch-bar to its upper position upon completion of the return motions of said elements to enable the forming anvil to present the cut-off blank into position ready for forming and driving during the next succeeding complete oscillation of said cam plate.

WILFRED KIRBY.
